PALLADIUM COMPLEXES AS PHOTOGRAPHIC EMULSION STABILIZERS

Robert E. Stauffer and William F. Smith, Rochester, N. Y., assignors to Eastman Kodak Company, Rochester, N. Y., a corporation of New Jersey

No Drawing. Application March 5, 1948,
Serial No. 13,352

5 Claims. (Cl. 95—7)

1

This invention relates to fog-inhibiting agents and stabilizers for photographic emulsions and to photographic emulsions containing them.

It is known that photographic emulsions, particularly ultra-sensitive emulsions or those containing optical sensitizers exhibit a tendency to form upon development a deposit of silver in the emulsion. This deposit extends more or less uniformly over the entire emulsion and is known as fog. Photographic fog is of two types: local and general. Local fog is formed by exposure of the film or plate at undesired points as by a light leak in the camera. General fog is formed in a number of ways. It may be caused by the conditions under which the film or plate is stored, such as conditions of high temperature or humidity or unusually long time of storage. The nature of the emulsion may also produce general fog as well as the conditions of development of the emulsion as by development for protracted periods of time or at temperatures above normal. We are primarily concerned with fog and sensitivity changes produced in films or plates on development after storage under adverse conditions of high temperature and humidity or both.

General fog and loss of sensitivity of the emulsion are especially likely to occur when the sensitive material is stored under conditions other than ideal, that is, under conditions of high temperature and humidity as in tropical regions.

It is an object of the invention to provide novel anti-fogging or fog-inhibiting compounds for emulsions. A further object is to provide anti-fogging agents which stabilize the initial sensitivity of the emulsion. A still further object is to provide anti-fogging agents which improve the keeping of the emulsion in tropical regions. Other objects will appear from the following description of our invention.

These objects are accomplished by incorporating in a silver halide emulsion an anionic palladium complex salt such as alkali metal or alkaline earth metal thiocyanato palladites, nitrito-palladites, bromo-nitritopalladates, and ammonium nitritopalladite. For example, we may use potassium thiocyanato palladite, $K_2Pd(CNS)_4$; calcium thiocyanato palladite, $CaPd(CNS)_4$; potassium nitrito palladite, $K_2Pd(NO_2)_4$; barium nitrito palladite, $BaPd(NO_2)_4$; potassium bromo-nitrito palladate, $K_2PdBr_2(NO_2)_4$, or ammonium nitritopalladite, $(NH_4)_2Pd(NO_2)_4$. Other similar anionic palladium complexes which have not been satisfactory, particularly because of fog-

2

ging properties or desensitizing action on the photographic emulsion include ammonium and potassium cyano palladites and ammonium thiocyanato palladite.

5 The object of our invention is to maintain the sensitivity and fog of silver halide emulsion at or close to initial optimum values under keeping conditions of high temperature and humidity. The fog inhibitors which we propose to use are 10 added to the emulsion during the process of manufacture to avoid loss of sensitivity and to inhibit the growth of incubation or keeping fog with passage of time under non-ideal conditions of storage.

15 A solution of the compounds of the invention when added in suitable concentration before coating to unsensitized or optically sensitized photographic emulsions does not affect appreciably the sensitometric values for sensitivity and 20 fog when measurements are made soon after coating. When sensitometric measurements are made after appreciable intervals of time under tropical or dry conditions of storage at elevated temperatures, however, the compounds stabilize 25 photographic speed and in certain cases maintain fog at a low level.

30 The preparation of silver halide emulsions involves three separate operations, (1) the emulsification and digestion or ripening of the silver halide, (2) the freeing of the emulsion from excess soluble salts usually by washing, (3) the 35 second digestion or after-ripening to obtain increased sensitivity (Mees, The Theory of the Photographic Process, 1942). We prefer to add the fog-inhibiting agents after the final digestion or after-ripening although they may be added before digestion. The most useful concentration range of fog inhibitor is from 0.26 to 3.9 gm. 40 of fog inhibitor per kilogram of silver nitrate used in making the emulsion and converted to silver halide. This amount will vary, e. g., depending upon the particular silver halide used.

45 The antifoggant and stabilizing action was determined by incubation of the emulsions under simulated tropical conditions and also by incubation in dry heat at 120° F. for various lengths of time from 6 days to 2 months. The results of these ageing tests are tabulated below and are 50 compared with the initial speed, gamma and fog of the emulsion without the stabilizing compounds. The tests from which the following tabulation was made used a high-speed orthochromatic negative type of emulsion exposed on an Eastman Type IIB sensitometer and devel-

oped for five minutes in a developer of the following composition:

	Grams
Monomethyl paraminophenol sulfate	2.5
Sodium sulfite (desiccated)	30.
Hydroquinone	2.5
Sodium metaborate	10.
Potassium bromide	0.5
Water to one liter.	

The results of the comparative tests are as follows:

It will be noted from the data in the above table that the improvement in fog and speed stability using the compounds of the invention is appreciable as compared with emulsions containing no inhibitor. Another advantage of our invention is that the compounds may be prepared easily and with high purity compared to organic types of inhibitors. Another and perhaps chief advantage is the greater extent of stabilizing action over a wide range of climatic conditions.

In use, the fog inhibitor is dissolved in water

of these. The dispersing agents may be gelatin or other colloid such as collodion, albumen, cellulose derivatives, or synthetic resins.

It will be understood that we contemplate as included within our invention all modifications and equivalents falling within the scope of the appended claims.

What we claim is:

1. A silver halide emulsion containing an anionic palladium complex salt selected from the group consisting of alkali metal and alkaline earth metal thiocyanato palladites, alkali metal and alkaline earth metal nitritopalladites, alkali metal and alkaline earth metal bromo-nitritopalladates and ammonium nitritopalladite.

2. A silver halide emulsion containing an alkali metal thiocyanato palladite.

3. A silver halide emulsion containing an alkali metal nitritopalladite.

4. A silver halide emulsion containing ammonium nitritopalladite.

5. A light-sensitive photographic element comprising a silver halide emulsion layer and a colloid layer contiguous to said emulsion layer, at least one of said layers containing an anionic palladium complex salt selected from the group consisting of alkali metal and alkaline earth metal thiocyanato palladites, alkali metal and alkaline earth metal nitritopalladites, alkali metal and alkaline earth metal bromo-nitritopalladates, and ammonium nitritopalladite.
